UNITED STATES PATENT OFFICE.

ALBERT PATITZ, OF MERIDEN, CONNECTICUT, ASSIGNOR TO THE BRADLEY & HUBBARD MFG. CO., OF SAME PLACE.

DESIGN FOR A BASE FOR LAMPS.

SPECIFICATION forming part of Design No. 25,873, dated August 4, 1896.

Application filed July 2, 1896. Serial No. 597,912. Term of patent 3½ years.

To all whom it may concern:

Be it known that I, ALBERT PATITZ, of Meriden, in the county of New Haven and State of Connecticut, have invented a new Design for a Base for Lamps, (Case C;) and I do hereby declare the following, when taken in connection with the accompanying drawing and the letters of reference marked thereon, to be a full, clear, and exact description of the same, and which said drawing constitutes part of this specification, and represents a perspective view of a lamp-base embodying my design.

This invention relates to a design for a base for lamps; and the design consists in the configuration and ornamentation as shown in the accompanying illustration and hereinafter described.

The base is rectangular in general outline, consisting of four legs A and four connecting-panels B, surmounted by a crown C. The legs A curve gradually downward and sharply upward, forming upturned feet D. The legs are ornamented by an intricate scroll and

floriated decoration E, covering the lower portion thereof, the upper portion at the junction of the legs with the crown being ornamented by a raised oval panel F, set in a scroll-like frame G. The connecting sides B consist of plain oval panels surrounded by a scroll and floriated border, the lower portion of which forms a rose and leaf ornamentation H. The surmounting crown is ornamented by a shell portion I, above which is a foliated band J, above which a plain neck curves inward and outward, terminating in a beaded ring K, all as shown in the accompanying illustration.

I claim—

The design for a base for lamps, as herein shown and described.

In testimony whereof I have signed this specification in the presence of two subscribing witnesses.

ALBERT PATITZ.
